CABINET WITH SEWING MACHINE RAISING
AND LOWERING MECHANISMS

Daniel H. Chason, Elizabeth, N. J., assignor to
The Singer Manufacturing Company, Elizabeth, N. J., a corporation of New Jersey

Application September 14, 1946, Serial No. 697,139

7 Claims. (Cl. 312—29)

1

This invention relates to sewing machine cabinets and more particularly to cabinets having a mechanism whereby a sewing machine can be lowered into the cabinet for storage or raised to a position atop the cabinet for use.

A primary object of the present invention is to provide an improved sewing machine cabinet in which the various parts are arranged for optimum safety, convenience and utility.

Another object of the invention is to provide a cabinet having an improved mechanism for raising and lowering a sewing machine.

A specific object of the invention is to provide an improved sewing machine raising and lowering mechanism arranged so that a single cabinet member provides the major rigid support afforded the mechanism.

Another specific object of the invention is to provide an improved sewing machine raising and lowering mechanism that will function properly regardless of minor dimensional inaccuracies caused by warping of the cabinet or improper installation.

Still another specific object of the invention is to provide an improved sewing machine raising and lowering mechanism in which the weight of the sewing machine, when in the sewing position, acts to maintain the machine in this position.

Other important objects of the invention will be apparent from the following detailed description and appended claims.

For a complete understanding of the invention reference should be made to the accompanying drawings in which—

Fig. 1 is a longitudinal sectional view of the sewing machine cabinet and the raising and lowering mechanism embodying the invention; the sewing machine platform being lifted slightly above sewing position of the machine;

Fig. 2 is an enlarged longitudinal sectional view of a portion of the cabinet and mechanism shown in Fig. 1, with the sewing machine platform in its normal raised position;

Fig. 3 is a transverse sectional view taken along the line 3—3 of Fig. 1 and looking in the direction of the arrows;

Fig. 4 is a perspective view of the raising and lowering mechanism, shown detached from the cabinet;

Fig. 5 is a fragmentary view taken along the line 5—5 of Fig. 3 and looking in the direction of the arrows;

Fig. 6 is a fragmentary vertical sectional view taken through a lower portion of the sewing machine cabinet;

2

Fig. 7 is a longitudinal sectional view of a modified raising and lowering mechanism embodying the invention, with the sewing machine platform in its normal raised position;

5 Fig. 8 is a transverse sectional view taken along the line 8—8 of Fig. 7 and looking in the direction of the arrows;

Fig. 9 is a fragmentary sectional view taken on the line 9—9 of Fig. 7 and looking in the direction of the arrows;

10 Fig. 10 is a fragmentary plan view taken along the line 10—10 of Fig. 7 and looking in the direction of the arrows; and

Fig. 11 is a fragmentary sectional view taken 15 substantially along the line 11—11 of Fig. 7 and looking in the direction of the arrows.

In the preferred embodiment of the invention illustrated in Figs. 1 to 6 inclusive the numeral 18 indicates a sewing machine of any well known type arranged to be housed in a wooden sewing machine cabinet 11 that may be similar to the cabinet shown in Design Patent No. 146,383, dated February 18, 1947, by J. L. Ray. A fixed horizontal cabinet-top 12, having a sewing machine receiving aperture 13, is supported by a pair of side legs 14 and 16, and a shelf 17 extends horizontally between the legs; being supported therefrom by a plurality of angle braces 18 held in place by wood screws 19. A back wall 21 and a front portion 21' are supported by the legs 14 and 16 by any known means. The front portion 21' preferably is in the form of a pair of doors similar to those shown in the above mentioned design application. Also the aperture 13 in the top 12 may be closed, when the sewing machine is in the lowered position, by a detachable cover-top (not shown) but which preferably is oval shaped and similar to the cover-top shown in the Design Patent No. 146,383.

20 40 A raising and lowering mechanism 27, which is shown completely assembled in Fig. 4, is housed in the cabinet 11. The upper angle-brackets 29, 30, 31, 32 and 33 of the mechanism 27 are secured to the under surface 34 of the apertured

45 table top 12 by a plurality of screws 28. Each of the brackets 29, 30, 32 and 33 has a horizontal arm 36 and a vertically depending arm 37, the latter being bent and pointed to provide a horizontally disposed journal pin 38. The brackets

50 55 29 and 30, when properly spaced and secured to the table-top 12, pivotally carry a support or hook-operating-bar 39 on the pins 38. The central horizontal portion of the support 39 is in the form of a manually operable angle bar, one web of which is apertured by an elongated hole 41. Each end of said apertured web is extended be-

yond the angled portion of the support and then is bent downwardly to form front and rear depending arms 42 and 43 respectively. Each of said arms is apertured as at 44 to receive one of the journal pins 38, and each depending arm is provided with at least one supporting member in the form of a J-shaped hook 46. The lower end of the front arm 42 has a V-shaped inclined cam surface 47, the function of which will hereinafter appear. The lower end of the rear arm 43 is bent 90 degrees, twisted, and then formed into a pivot pin 48 for entering a hole in a releasing link 49. In like manner, the brackets 32 and 33, when properly spaced and secured to the table-top 12, pivotally carry a support 51 on their journal pins 38. The central horizontal portion of the support 51 is in the form of an angle bar, one web of which is notched by an elongated slot 52. Each end of said notched web is extended beyond the angled portion of the support and then is bent downwardly to form front and rear depending arms 53 and 54 respectively. Each of said arms is apertured as at 44 to receive one of the journal pins 38, and each depending arm is provided with a hook 46. The lower end of the rear arm 54 is bent 90 degrees, twisted, and then formed into a pivot pin 48 for entering a hole in a releasing link 56.

The links 49 and 56 extend from opposite ends of the raising and lowering mechanism toward a central point, where holes 57 and 58, respectively in the links 49 and 56, are entered by the opposite pivot ends 59 and 60 of a link connector 61, which is pivotally mounted on a rivet 62. The rivet is carried by the angle bracket 31 which has already been shown to be attached to the table top by screws 28. A tension spring 63, Figs. 2 and 4, extends between an angled arm 64 of the bracket 31 and the end 59 of the link connector 61, thereby biasing the connector 61, the links 49 and 56, and the supports 39 and 51 to the closed position with the connector abutting a stop 118, as best shown in Figs. 2 and 4.

In addition to the hereinbefore described upper brackets 29, 30, 31, 32 and 33, which are secured to the cabinet-top 12, there are provided two lower angle brackets 66 and 67, which are secured to the leg members 14 and 16 and also to the shelf 17 by means of a plurality of wood screws 68. The horizontal web of each angle bracket 66 and 67 has an elongated hole 69, the longer dimension of which extends in the same direction as the longitudinal dimension of the sewing machine cabinet 11. Each of the upper brackets 30 and 32 are provided with a cylindrical hole 71, and when the raising and lowering mechanism is assembled in the cabinet, the lower brackets 66 and 67 are positioned in such a manner that each hole 69 is located vertically below one of the holes 71.

A slide rod 72 extends vertically from the bracket 66 through the hole 41 to the bracket 30, and opposite ends of the rod, which are both reduced in diameter, enter the holes 69 and 71. In like manner a slide rod 73 extends from the bracket 67 through the opening 52 to the bracket 32, and opposite ends of the rod enter the holes 69 and 71. From this it can be seen that the lower ends of the rods 72 and 73 are free to move slightly laterally for self-positioning purposes.

A sewing machine carrying-platform 74 is slidably mounted for vertical movement on the rods 72 and 73. To this end, vertically disposed guide-sleeves 76 are suitably secured to two angle-bar end-rails 77 and 78 of the platform 74. Cushion

springs 79 (Fig. 3) embrace the guide-sleeves 76 and are each supported by a pair of Z-shaped brackets 81, each bracket being held in position by a screw 82 threaded into the under side of the end-rails 77 and 78. The end-rails 77 and 78 are connected by front and rear angle-bar rails 83 and 84 respectively, and each of the latter carries a sewing machine positioning angle-bracket 86. An intermediate rail 87 extends between and is carried by the two rails 83 and 84, and the intermediate rail carries an adjustable sewing machine clamp 88, which can be secured to the rail 87 in machine holding position by screwing a thumb nut 89 onto a threaded stud 91. When the nut 89 and clamp 88 are loosened, the sewing machine 10 can be removed from the platform 74, thus making the sewing machine available as a portable unit. A tray 92, for holding bobbins and other appurtenances, extends between and is supported from the rails 77, 83, 84 and 87. Also each of the end-rails 77 and 78 is apertured by a pair of rectangular holes 93 functioning as keepers which are arranged to be engaged by the latching members or hooks 46 in a manner hereinafter described.

Special attention is directed to Fig. 2 wherein the particular shape and position of the hooks 46 and the holes 93 are most advantageously shown. Each hook 46 has a pointed upstanding finger portion 95 for entering one of the holes 93 and also has a flat portion 100 for supporting the platform 74. It will be noted that the weight of the sewing machine 10 and the platform 74 tends to open the hooks 46, but due to the latching or hooking action of the fingers 95 in holes 93 on opposite ends of the platform, tension develops in the platform members. This force acts on the finger portions 95 and maintains the hooks in supporting position, thus preventing the platform from being lowered until it has first been raised a sufficient distance to clear the top of the hook portions 95. To this end, each of the depending arms 42, 43, 53 and 54 has a vertically cutaway portion 94 which allows the platform 74 to be raised a short distance above the top of the fingers 95 without moving the arms. The fact that the hooks 46 cannot be moved until the platform 74 is raised, assures against accidental release and thus accidental dropping of the sewing machine and the platform into the storage cabinet 11.

Attention is also directed to the relative location of the cam surface 47 and the outer edge 96 of the rail 77. When the sewing machine 10 and the platform 74 are in the process of being raised from the lowermost position to the raised position, the edge 96 engages the surface 47 thereby pivotally moving the support 39 on the journal pins 38. This causes the link 49 to be shifted longitudinally of its length and thereby to pivotally turn the link connector 61 against the action of the spring 63. Movement of the connector 61 causes longitudinal movement of the link 56, which in turn pivotally moves the support 51 on the journal pins 38 of the brackets 32 and 33. This automatically moves the four hooks 46 out of the vertical line of movement of the platform 74 and allows the platform to be raised to the fully raised position. When the platform 74 has been fully raised the biasing spring 63 moves the arms 42, 43, 53 and 54 to the supporting position shown in Fig. 1 by solid lines.

Figs. 4 and 6 show that the lower end of the rod 72 (and this also applies to the rod 73) is not rigidly secured to the bracket 67, but due to the

elongated hole 69, a slight lateral movement of the rod 72 (and also rod 73) is permitted. This movement of the rods 72 and 73 compensates for minor dimensional inaccuracies of the cabinet or mechanism, and also allows for any shrinkage that may occur as the cabinet ages.

In order to lower the sewing machine 10 from the working position, atop the cabinet to the stored position shown in dotted lines in Fig. 1 it is simply necessary to grasp the sewing machine 10 with the right hand 97 and to lift the machine and platform 74 a sufficient distance to disengage the rectangular holes 93 from engagement by the hooks 46. At the same time, the left hand 98 is used to press the hook operating bar 39. This causes the arms 42 and 43 to pivot on the pins 38. The lower end of the arm 42 enters a recess 99 appropriately provided in the leg 14, and both hooks 46 move outwardly from their positions below the rail 77. Movement of the arm 43 operates the link 49, link connector 61, link 56, support 51, and arms 53 and 54. Movement of the latter moves both hooks 46 from their position below the rail 78. When this has occurred, it is possible to lower the sewing machine and platform into the storage cavity provided in the cabinet 11. Should the sewing machine be accidentally dropped, after the hooks have been released, the springs 79 will prevent damage that might otherwise occur to the sewing machine or cabinet.

In order to raise the sewing machine from the lowered or stored position, shown by dotted lines in Fig. 1, it is simply necessary to remove the cover top (not shown) from the cabinet, reach through the aperture 13 and then lift the sewing machine 10 and the platform 74. During this operation (see Fig. 4) the edge 96 of the rail 77 engages the cam surface 47 and thereby moves and holds the hooks 46 out of the line of travel of the rails 77 and 78 until the platform has been raised. When the sewing machine and platform have reached their uppermost position, the tension spring 63, functioning through the links 49 and 56, moves the arms 42, 43, 53, 54 and their hooks 46 to the closed position. Then the sewing machine and platform are slightly lowered until the hooks 46 are in locking or latching engagement with the holes 93. (See Fig. 2.) In this position, it is impossible (due to the engagement of the hooks 46 with the holes 93) for the arms 42, 43, 53, 54 and their hooks 46 to become inadvertently unlatched.

Figs. 7 to 11 illustrate a modified form of sewing machine raising and lowering mechanism, in which most of the brackets, operating links, and rods are secured to the movable platform instead of being secured to the wooden cabinet as in the previously described embodiment of the invention. Many elements of the mechanism appear in both of the illustrated structures, and therefore, parts that are identical or perform substantially the same functions in both constructions will be designated by the same reference numeral, but in the modified form the numeral will be followed by the exponent *m*.

The raising and lowering mechanism of the modified embodiment of the invention comprises a pair of brackets 101 and 102 which are secured to the under face 34^m of the apertured cabinet top 12^m by wood screws 28^m. Each end of each bracket 101 and 102 has a vertically depending arm 37^m, the lower end of which is bent outwardly to provide a horizontally disposed latch lug 103. A pair of slide rods 72^m and 73^m extend down-

wardly from holes 71^m which are provided in the center of each bracket 101 and 102, and a sewing machine carrying platform 74^m is slidably mounted for vertical movement on these rods. This platform has a pair of angle-bar end rails 77^m and 78^m which are connected by front and back angle rails 83^m and 84^m. At both ends of the upwardly disposed flanges of the rails 83^m and 84^m are holes 104 to journal left and right latch carrying shafts 106 and 107. At opposite ends of the shaft 106 are mounted upstanding latch members 108 and 109, whereas opposite ends of the shaft 107 mount upstanding latch members 111 and 112. A means for securing each latch to its shaft-end is provided, and includes a non-circular hole in the latch fitted to a non-circular end of the shaft, and a screw 113 that enters a threaded hole coaxially tapped into the shaft.

Each of the four latches has a hooked member 46^m, which comprises a cutaway portion 94^m, a horizontal flat surface 100^m, and a depending finger 95^m. In addition, the front left hand latch 108 has an inclined cam surface 47^m and a horizontally extending arm 114; the latter carrying a finger pad 116, by the operation of which the four latches may be moved to the unlatched position. The left hand rear latch 109 is provided with a depending arm 117 that is bent backwardly 90 degrees, twisted, and then formed into a pivot pin 48^m for entering a hole in a releasing link 49^m. In like manner, the right hand rear latch 111 has a depending arm which is bent backwardly 90 degrees, twisted, and then formed into a pivot pin 48^m for entering a hole in a second releasing link 56^m. The front right hand latch 112 acts merely as a latch, and is not provided with additional arms or levers.

The links 49^m and 56^m extend from opposite ends of the carrying platform 74^m toward a central point where holes 57^m and 58^m therein are entered by pivot ends 59^m and 60^m of a link connector 61^m. The link connector is pivotally mounted on a rivet 62^m, the rivet being carried by the upstanding flange of the rear rail 84^m. A tension spring 63^m (Figs. 7 and 10) extends between an offset arm 64^m carried by the rail 83^m and an end of the link connector 61^m, thereby biasing the connector, the links and the latches to the closed position best shown in Fig. 7. An upstanding stop lug 118^m is engaged by the link connector 61^m and thereby limits its motion in a clockwise direction as viewed in Fig. 7.

When the platform 74^m is in the position shown in Fig. 7, the weight of the platform and a sewing machine carried thereby, tends to hold the latches in their closed position thus preventing the platform from being lowered until it has first been raised a distance sufficient to cause the bottom of the fingers 95^m to be well above the latch lugs 103.

While I have illustrated the present invention as applied to a specific sewing machine and as applied to a specific cabinet, it is to be understood that the invention is equally applicable to other types of sewing machines and cabinets.

Having thus set forth the nature of the invention, what I claim herein is:

1. A sewing machine cabinet comprising an apertured fixed cabinet-top member, a pair of legs supporting said cabinet-top member, a shelf connecting said legs at a point below said cabinet-top member, a pair of upstanding rods extending between said shelf and said cabinet-top member, a sewing machine carrying member slidably movable on said rods, a latch means on one of said members, and a J-shaped hook pivotally carried

by the other of said members and arranged to engage latch means on the first of said members, said hook having a finger portion locking said pivotal hook in engaging position while it is supporting said platform and said hook also having a vertically cutaway portion which permits raising said sewing machine carrying member a short distance without moving said hook.

2. A sewing machine cabinet comprising an apertured fixed cabinet-top, a pair of leg members supporting said top, a shelf member connecting said leg members at a point below said cabinet-top, a pair of vertically positioned rods extending between said shelf member and said cabinet-top, an apertured sewing machine carrying platform slidably movable on said rods, and a pair of J-shaped hook members pivotally carried by said cabinet-top; said hook members having a finger portion arranged to engage said apertured carrying platform, and also having vertical cutaway portions which permit raising said platform a short distance without moving said hook members.

3. A raising and lowering mechanism for use with a sewing machine cabinet comprising, a sewing machine carrying platform mounted for vertical movement in said cabinet, a plurality of latch lugs secured to said sewing machine cabinet, and a plurality of latch members pivotally supported by said sewing machine carrying platform and arranged to engage said latch lugs when said sewing machine carrying platform is in a raised position, and a manually operable mechanism for simultaneously pivoting said plurality of latch members, said mechanism being ineffective for moving said latch members when said latch members are supporting the weight of said platform and providing for moving said latch members simultaneously when the weight of said platform is removed from said latch members.

4. In a sewing machine cabinet, a sewing machine supporting platform mounted for vertical movement in said cabinet, a plurality of spaced movable latch members for supporting said platform in a predetermined position, spaced members engaged by said movable latch members, a mechanism connecting said plurality of movable latch members for simultaneous movement, and a finger portion on each of said movable latch members, some of said members being carried on said cabinet and other of said members being carried on said platform and said finger portions locking said movable latch members in latching engagement while they are supporting said platform.

5. In a sewing machine cabinet, a sewing machine supporting platform of rectangular form mounted for vertical movement in said cabinet, four pivoted latch members supported from said cabinet and positioned approximately the same distance apart as the four corners of said sewing machine supporting platform, keeper members located adjacent the four corners of said platform, a hook carried by each of said pivoted latch members and each hook engageable with one of said keeper members thereby to support the

platform in such a manner that when the weight of said platform is thus carried said latch members will be maintained in latching engagement, and a manually operable mechanism, including a pair of links and a pivoted link connector interposed therebetween, for simultaneously operating all of said pivoted latch members, said mechanism being ineffective for moving said latch members when said latch members are supporting the weight of said platform and providing for moving said members simultaneously when the weight of said platform is removed from said latch members.

6. The combination with a sewing machine cabinet including an apertured horizontal cabinet-top having a lower face, and supporting leg members with a back and shelf connecting said leg members, of a raising and lowering mechanism, comprising, means for rigidly supporting a portion of said mechanism from said lower face of said cabinet top, non-rigid means for supporting a portion of said mechanism from said shelf, said non-rigid means including a bracket secured to said shelf and having an elongated hole therein, and a vertically extending rod of which the lower end enters said elongated hole formed in said bracket carried by said shelf.

7. A raising and lowering mechanism for use with a sewing machine, comprising, a cabinet member, a sewing machine carrying platform member mounted for movement within said cabinet member, a keeper carried by one of said members, a pivotally supported device carried by the other of said members and so constructed and arranged as to engage said keeper and thereby support said platform member within said cabinet member, and a finger formed integral with said pivotally supported device, said finger being of such configuration as to engage said keeper thereby preventing disengaging pivotal movement of said pivotally supported device while said pivotally supported device is supporting said platform member, and said pivotally supported device having a cutaway portion that permits movement of said platform member thereby allowing disengagement of said finger from said keeper.

DANIEL H. CHASON.
